UNITED STATES PATENT OFFICE.

EVERETT B. FEWELL, OF MADISON, INDIANA.

ARTIFICIAL TOOTH.

1,078,844.

Specification of Letters Patent. Patented Nov. 18, 1913.

Application filed October 26, 1912. Serial No. 727,907.

To all whom it may concern:

Be it known that I, EVERETT B. FEWELL, a citizen of the United States, residing at Madison, in the county of Jefferson and State of Indiana, have invented a new and useful Artificial Tooth, of which the following is a specification.

The present invention relates to improvements in artificial teeth, the primary object 10 of the invention being the provision of a novel means whereby the metal support or backing for the tooth is properly shaped and placed in position either as a pivot or bridge previously to the attachment thereto 15 of the porcelain front or facing of the tooth, thus avoiding the attendant cracking or breaking of such front or facing due to the excessive heat necessary to the formation of the metal support or backing.

20 A further object of the present invention is the provision of an artificial tooth having a detachable front or facing secured fixedly to the backing in a practical and durable manner.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

35 In the drawings—Figure 1 is a perspective view taken from the rear of the complete tooth. Fig. 2 is a rear perspective view of a front or facing of the tooth. Fig. 3 is a rear plan view thereof. Fig. 4 is a 40 vertical central sectional view through a complete tooth. Fig. 5 is a perspective view of the lower front portion of the swaged metal insert. Figs. 6 and 7 are detail views of the sleeve and rod used for connecting the 45 facing to the backing.

Referring to the drawings, the numeral 1 designates the metal solder backing, to which may be attached the usual pivot or bridge (not shown).

50 A sheet metal insert 2 is provided, the same being swaged as will presently appear to provide the necessary co-acting attaching means for the front or facing 3. The portion 1 is preferably made of a gold or other

suitable solder while the insert 2 is sheet 55 gold, platinum or other suitable metal, the front or facing 3 being made of porcelain or other similar material. The insert 2 is swaged or shaped to provide the depression having the recessed portion 4 and the inclined lower lip 5 terminating in the rim 5', which with the lower portion of the backing 1 is upon the biting edge of the tooth when complete. Thus a metal biting edge for the facing 3 of porcelain preferably is provided. 60 The facing 3 is therefore provided with an abutment 3' upon its rear face shaped to have the upper lip or flange 6 fit into the recessed portion 4 of the insert 2, its inclined faces 8 being co-extensive with and abutting 65 the inclined portions 7 of the insert 2 while the lateral wings 9 of the insert 2 engage the flat portions 10 of the front 3. The lower lip 5 engages the inclined lower face 12 of the facing 3, thus permitting the facing 3 70 to seat closely against the insert 2 which is soldered to and carried by the backing 1. Thus the front is held against upward movement but not against outward movement and it is therefore desirable and necessary that 75 the lower end of the front be secured to the backing 1 and insert 2 in a fixed position. In order to accomplish this a double diameter bore or socket 13 is formed within the lower end and centrally of the front 3, thus 80 providing the shouldered portion 14 for the reception of the short sleeve or tube 15, which is soldered to and carried by the insert 2, with a slight portion as at 15' projecting below the inclined face 5 of the insert. 85 When the parts are assembled the relatively thin lower inclined edge 1' of the backing 1 is below the lip 5 of the insert 2 and surrounds the lower end 15' of the tube 15 so that the extreme lower edge of 90 the tube is flush with the lower face of the backing. Thus the lower end 15' forms a means to assist in locking the insert to the 95 backing 1.

Driven through the lower open end of 100 the tube 15 and having its upper end seated within the reduced end of the bore 13 is a securing pin 16, whose upper end is flattened as at 17 so as to provide a means to permit of the displacement of any cement that is 105 placed within the bore, and so that such cement will not interfere with the complete seating of the pin, as clearly illustrated in

Fig. 4. The lower end 18 of the pin is inclined so as to be flush with the surrounding portion of the sleeve 15 and backing 1.

It is evident from the foregoing that any pressure upon the porcelain facing will be taken care of by the shoulder 6 which locks with the backing, and that the pin 16, being the last member to finish the locking of the facing, may or may not be dipped into cement before forcing the pin home.

The lower end of the pin as before described is cut even with the soldered backing and is preferably burnished, said pin serving only to lock the facing in place and withstand any pressure forwardly that may occur upon the facing. Should the facing be tipped, as herein shown, no such forward pressure will result but where the same is not tipped there may be a very slight forward pressure.

These facings are indicated in posterior bridge teeth as well as the "Richmond" type crowns and also anterior bridge teeth. The facings are also numbered and these numbers correspond with similar numbers stamped upon the backings, thus providing a means whereby the facings may be readily fitted to their proper backings.

In this form of tooth no investing of the porcelain during the soldering process is necessary, thus avoiding the bad effect that the heat would have upon the porcelain, while the complete tooth can be handled similarly to a pin tooth, the backing being made when necessary by the dentist by swaging out of pure gold.

Where the sleeve 15 is attached to the insert 2, the same is soldered and then reswaged so that the same is placed for proper alignment with the enlarged portion of the bore 13. The backing and tube are then filled with suitable investing material and soldered to the desired thickness.

The lower edge of the porcelain facing

being beveled, enables the dentist to metal 45 tip the edge as heavy as may be desired to form a metal cutting edge for the tooth.

What is claimed is:

1. An artificial tooth having a metal backing, provided with a depression having a 50 recessed portion at one end, a detachable facing for the backing having an abutment for fitting the recessed portion and held against movement in one direction thereby, and means for engaging the backing and 55 facing to lock the facing to the backing.

2. An artificial tooth having a metal backing provided with a depression having a recessed upper portion and an inclined lower portion forming a biting end, a sheet of 60 metal lining the depression and adjacent face of the backing, a facing having an abutment for fitting co-extensively upon the lining, and coacting means carried by the lining and facing for locking the facing to the 65 backing.

3. An artificial tooth having a metal backing provided with a depression having a recessed upper portion and an inclined lower portion forming a biting end, a sheet of 70 metal lining the depression and adjacent face of the backing, a facing having an abutment for fitting co-extensively upon the lining, a sleeve carried by the lining and engaging a portion of the biting end of 75 the backing, said facing being provided with a socket for the reception of the sleeve, and a pin insertible through the sleeve into the socket for securing the facing to the lining and backing.

In testimony that I claim the foregoing as my own, I have hereto affixed my signature in the presence of two witnesses.

EVERETT B. FEWELL.
